[57] **CLAIM**

The design for a tripod head, as shown and described above.

DESCRIPTION

FIG. 1 is a perspective view of my new design for a tripod head;

FIG. 2 is a front view of my new design;

FIG. 3 is a rear view of my new design;

FIG. 4 is a left side view of my new design;

FIG. 5 is a right side view of my new design;

FIG. 6 is a top view of my new design; and,

FIG. 7 is a bottom view of my new design.

The broken line showing the fragmentary leg portion is for illustrative purposes and forms no part of the claim design.

FIG. 1

FIG. 2

FIG. 3

FIG. 5

FIG. 4

FIG. 6

FIG. 7
